DETACHABLE TOP MEMBER FOR A CONTAINER

Paul Andrew Lapidus, Monterey, Calif., assignor to American Can Company, New York, N.Y.

Filed Oct. 2, 1969, Ser. No. 19,390

Term of patent 14 years

Int. Cl. D9—99

U.S. Cl. D9—253

FIG. 1 is a perspective view of a detachable top member for a container showing my new design;

FIG. 2 is a side elevation view thereof;

FIG. 3 is a top plan view thereof;

FIG. 4 is a bottom plan view thereof.

I claim:

The ornamental design for a detachable top member for a container, substantially as shown.
